UNITED STATES PATENT OFFICE

FRANK J. PETERS, OF PORTLAND, OREGON, ASSIGNOR OF ONE-HALF TO IRVING J. BOYCE, OF PORTLAND, OREGON

TOY COAST DEFENSE GUN

Application filed March 2, 1932. Serial No. 596,267.

My invention relates to toy disappearing guns simulating coast defense guns.

The invention is comprised primarily of a base to which a gun mounting is rotatably attached. A gear rack segment is associated with the base and a manually manipulative pinion is associated with the gun mounting and coacts with the gear rack segment to train the gun in the desired direction.

10 The gun barrel and breeching are mounted upon suitable link supports so that when the gun is fired it automatically raises to firing position before the projectile is released. Reacting elements as springs are disposed at the oppositely disposed sides of the barrel and the legs of a cross yoke are adapted to the reacting elements. The cocking of the gun is accomplished by a manually manipulative lever which loads the springs 15 and maintains the cross yoke locked until the barrel assembly has reached a predetermined elevation at which time the same is released and the projectile is simultaneously fired. The gun barrel assembly is brought 20 to normal repressed position through the rebound. The breeching is open at the top to facilitate the placing of the projectile therein. The rebound of the gun barrel assembly is checked by a cushion.

25 One of the objects of my invention, is to provide a toy gun that simulates a coast defense gun.

30 A further object of my invention consists in providing a simply constructed gun and gun mounting, through the use of which children may have available a toy that may be used but that is harmless in its operation.

35 A still further object of my invention consists in so constructing the gun that it will have the action of a large piece and will rise to firing position, will release the projectile while in the raised position and will automatically return to a state of repose and for loading.

40 45 A still further object consists in so constructing the gun that it will be comprised of but few parts and so the same may be used by children over relatively long operating with a minimum of operating annoyance.

50 With these and incidental objects in view,

the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a side view of the assembled device.

Fig. 2 is a top, plan view of the assembled device.

Fig. 3 is a sectional, plan view of the assembled device, the same being taken on line 3—3 of Fig. 1, looking in the direction indicated.

Fig. 4 is a fragmentary, sectional, plan view of the assembled device illustrating the projectile in place within the breeching.

Fig. 5 is a sectional, side view of the assembled device.

Fig. 6 is a sectional, side view of the assembled device illustrating the gun in full raised position and before the discharge of the projectile therefrom.

Fig. 7 is a sectional, end view of the mechanism in the position as illustrated in Fig. 6, the same being taken on line 7—7 of Fig. 6, looking in the direction indicated.

Fig. 8 is a fragmentary, sectional side view of the rear gun mounting support shown in full raised position.

Fig. 9 is a plan view of the base of the gun mounting.

Fig. 10 is a plan view of the turn table upon which the base of the gun mounting is mounted.

Like reference characters refer to like parts throughout the several views.

I preferably mount the gun upon any suitable base 1. A gun support 2 is mounted upon the base 1. The gun support and the base being pivotally secured together about a king pin 3. The king pin 3 has a relatively large head 4 that is disposed within a recess on the underside of the base and the king pin is threaded upon its upper end and to which suitable lock nuts 5 are mounted to provide a turning support about which the

gun mounting 2 may be made to partially rotate.

A parapet 6 is disposed at the front, or discharge end of the gun mounting, the same having a sloping surface 7 upon its forward, or front end. The parapet forms a pillow block for the journaling of a journal shaft 8 and the links 9 and 10 are secured to and are journaled relative to the shaft 8 upon their one end. A barrel assembly 11 is primarily supported upon its front end by the links 9 and 10. The links being journaled relative to the barrel assembly by the journal pins 12 and 13 that outwardly extend from the opposite disposed side of the mounting. The journal pins 12 and 13 are disposed substantially near the center of gravity of the gun barrel assembly. A breeching block 14 is disposed at the breeching end of the gun barrel assembly and an opening 15 is disposed within the breeching and through which the projectile 16 may be placed.

A cross yoke 17 is disposed within the breeching, the cross yoke terminating in parallelly disposed legs 18 and 19. The legs extend longitudinally of the mountings 20 and 21 respectively and reacting elements, as coil springs 22 and 23 are disposed within the mountings 18 and 19. The same are disposed about the parallelly disposed legs 18 and 19. The outer ends of each of the legs are threaded and to which plates 24 and 25 are secured to form a support for one end of each of the coil springs. The oppositely disposed ends of the coil springs rest directly upon the rear ends 26 and 27, of the mountings 20 and 21.

The rear end of the barrel assembly is supported upon a locking bar 28. The locking bar 28 is supported upon a journal shaft 29. The journal shaft 29 is fixedly disposed within suitable bracket supports 30. A loading lever 31 is hingedly secured to the breeching assembly as by being hinged relative to a cross shaft 32.

The legs of the loading lever 31 have a hand engaging U 33 disposed central of the loops over the gun barrel and may be so shaped as to form a rear sight for the gun.

A front sight 34 upwardly extends from the muzzle end of the gun.

The side legs of the loading lever pass through and engage the inner side of each of the parallelly disposed legs of the cross yoke 17. The cross yoke 17 has crimps 36 and 37 formed therein and against which the legs of the loading lever are made to engage. The legs of the loading lever are cam shaped, as illustrated at 38 so that as the cross yoke is rearwardly extended, and as the reacting elements 22 and 23 are compressed, a mechanical advantage will obtain upon the loading lever because of the increasing length of the fulcrum and of the length of the lever and the camming legs of the loading lever.

A locking notch 39 is disposed within the head of locking bar 28. The upward end of the head has a sloping surface 40 to adapt the cross yoke for sliding thereover and into the locking notch 39. A trigger 41 is pivotally disposed about a supporting pin 42 and a reacting element as coil spring 43 maintains the trigger in stopped engagement with the stop pin 44. A locking pin 45 is disposed upon the outer frame of the barrel and breeching assembly, and the same is adapted for engaging the sloping surface 46. When the locking pin 45 strikes the sloping surface 46 of the trigger it actuates the trigger against the reacting element 43 and the trigger lock engages the locking pin 45 and maintains the barrel and breeching assembly in normal repressed lowered position.

The projectile 16 is preferably placed within the breeching after the springs for projecting the projectile have been loaded and the cross yoke is engaged within the locking notch of the locking bar. The release of the trigger enables the loaded spring to react against the locking bar and to raise the gun and breeching assembly sufficiently to permit the cross yoke to disengage itself from the locking notch disposed within the locking head. The rebound permits the raised assembly to return to its normal lowered position in which position the same is locked through the action of the trigger assembly. A cushion block 47 absorbs the rebound and prevents the undue shocking of the base assembly mechanism.

A foot 48 prevents the overforward movement of the gun and breeching assembly. The range of the gun is predetermined by a rod 49 that is secured to a threaded block 50. The threaded block 50 is associated with a regulatory control link 51 that predetermines the relationship of the links 9 and 10, and therefore the elevation of the muzzle. A crank 52 is associated with the rod 49 and facilitates the positioning of the raising and the lowering of the elevation of the gun barrel.

The range of the projectile is predetermined by its placement relative to that of the cross yoke. It is also desirable to predetermine the length of projectile that may be placed within the breeching. This is accomplished by the placing of an adjustable breeching end of the opening through which the projectile is placed, the plate has a slot 57 disposed therein and the plate is clamped relative to the breeching assembly by a thumb nut 58. The thumb nut 58 is threadably secured to a screw 59 and the screw 59 extends through the slot 57. The barrel may be also moved longitudinally of its bearing support and be clamped in desired position by a set screw, 59A. This construction provides the length of a projectile that may be placed within a gun and also predetermines the

range of the gun and the distance that the projectile may be fired. An annular segment 60 is associated with the collar 55 and a pinion 61 is adapted to coact therewith. The 5 pinion 61 is secured to a crank 62 that turns the pinion and the gun mounting assembly relative to the base to thereby train the gun upon a target.

While the form of mechanism herein 10 shown and described is admirably adapted to fulfill the objects primarily stated, it is to be understood that it is not intended to confine the invention to the one form of embodiment herein shown and described, as it is 15 susceptible of embodiment in various forms, all coming within the scope of the claims which follow.

What I claim is:

1. In a device of the class described, the 20 combination of a base, a gun mounting rotatably mounted relative to the base, a barrel and breeching assembly pivotally mounted upon a pair of links and a locking bar, relative to the gun mounting, a cross yoke disposed transversely of the breeching and legs 25 extending parallelly with the barrel and toward the muzzle of the barrel, reacting elements associated with the legs, a loading lever associated with the cross yoke and adapted 30 for imparting longitudinal movement to the cross yoke and for loading the coil springs, a locking trigger disposed in the path of the cross yoke and adapted for maintaining the cross yoke in a retractive position, a loading opening disposed in the breeching and settable means for predetermining the length of the projectile that may 35 be placed within the breeching and to position the same relative to that of the cross yoke when the cross yoke is in retractive 40 position.

2. In a device of the class described, the 45 combination of a gun barrel and breeching rotatably mounted relative to a gun mounting disposed therebelow, links and a locking bar disposed between the breeching and barrel and the mounting, a cross yoke disposed within the breeching and having legs 50 that are disposed longitudinally of the barrel and disposed at either side of the barrel, a coil spring associated with each of the legs and adapted for being retracted when the cross yoke is retracted, means for loading the springs and for locking the yoke relative 55 to a trigger release, and settable means for limiting the position and the length of the projectile that may be placed within the breeching.

3. In a device of the class described, the 60 combination of a base, a gun mounting disposed upon the base, a gun barrel and a breeching indirectly mounted upon the gun mounting, a cross yoke mounted relative to the breeching, manually manipulative means 65 for loading the cross yoke, trigger means

for maintaining the cross yoke in a retractive position, associated means for raising the barrel and breeching when the cross yoke is released and for firing a projectile after the gun breeching and the barrel have been 70 raised, means for returning the gun breeching and barrel in a retracted position after the projectile is fired and means for predetermining the elevation of the barrel and the length of the projectile that may be placed in the breeching and for predetermining the distance that the projectile may be thrown.

4. In a device of the class described, the 75 combination of a gun mounting, a barrel and breeching gun assembly mounted upon the gun mounting, means for training the gun in the desired position, settable means for elevating the gun barrel for the desired projectile, means for loading a reactive element associated with the gun, means for locking the retractive element when loaded, means for initially raising the gun and breeching into elevated position before firing, means for firing the gun when raised, means for returning the barrel and breeching assembly to normal lowered position after being fired and settable means for limiting the length of the projectile to be placed within the gun breeching and for predetermining the distance the projectile may be thrown.

5. In a device of the class described, the 80 combination of a gun barrel and breeching, manually manipulative means for loading the gun, means for raising then firing and finally returning the gun to normal lowered 85 position as a sequence in each firing cycle, means for settable limiting the length of projectile that may be placed within the breeching and settable means for predetermining the angle of elevation of the barrel assembly 90 and the distance that the projectile may be thrown.

6. In a device of the class described, in 95 combination a base, a gun support rotatably disposed upon the base, manually manipulative means for rotating the gun relative to the base, a gun barrel and breeching mounted upon links and a locking bar, a cross yoke having legs associated therewith 100 mounted upon the barrel assembly, reacting elements associated with the legs of the cross yoke, lever means for loading the springs and the cross yoke, a locking head associated with the locking bar and adapted for maintaining the cross yoke retracted therein, a trigger 105 for maintaining the barrel assembly retracted when the cross yoke is disposed in the locking notch of the locking bar, and automatic means for releasing the cross yoke from the locking notch when the barrel assembly has been elevated for a predetermined amount.

FRANK J. PETERS.
